UNITED STATES PATENT OFFICE.

WILLIAM H. PLUMB, OF ANSONIA, CONNECTICUT.

DESIGN FOR A WORK-BASKET.

SPECIFICATION forming part of Design No. 21,187, dated December 1, 1891.

Application filed October 29, 1891. Serial No. 410,284. Term of patent 7 years.

To all whom it may concern:

Be it known that I, WILLIAM H. PLUMB, a citizen of the United States, residing at Ansonia, in the county of New Haven and State of Connecticut, have invented a certain new and original Design for Work - Baskets, of which the following is a specification, reference being had to the accompanying drawing, forming a part thereof, and which shows in perspective a work-basket or the like conformed and ornamented in accordance with my invention.

The leading feature of my design consists in the hexagonal box having the representation of scallop shells upon each of its exterior vertical faces.

In said drawing the receptacle is hexago-

nal or octagonal, as shown. It has a puffed and fluted exterior covering 1 and a similar lining 2. Its edge is gathered, as at 3, to form a frill or ruffle. Upon each of the vertical faces of the receptacle is the representation of a scallop shell 4, and the adjacent edges of the shells are joined by means of bows 5.

I claim—

The design for work-baskets and similar articles, substantially as herein shown and described.

In testimony whereof I affix my signature in presence of two witnesses.

WILLIAM H. PLUMB.
